WELL DEVICE

Herbert C. Otis, Dallas, Tex.

Application August 2, 1940, Serial No. 349,773

18 Claims.

(Cl. 103—232)

This invention relates to new and useful improvements in well devices.

One object of the invention is to provide an improved control device for use in flowing wells, which is arranged to permit an upward flow of the well fluids so long as the gas in said fluids is lifting or raising the oil; said device being constructed to substantially shut off upward flow to retard the production or flow of gas alone when such gas enters the production string, whereby the gas in the producing formation is conserved and is permitted to flow to the surface in appreciable volumes only when it is acting to raise the oil.

Another object of the present invention is to provide an improved well device for controlling the upward flow of well fluids through the production string in accordance with the rate of entry of the well fluids from the producing formation into the bore, whereby a liquid seal is at all times maintained around the inlet of the production string and the gas in the producing formation is conserved.

An important object of the invention is to provide an improved well device which operates as an intermitter and which is constructed so as to permit maximum efficient flow upwardly through the production string until such time as the liquid level in the well bore falls to a predetermined point, at which time said device closes to retard the flow to maintain a liquid seal around the production string inlet; the device reopening to again permit flow under predetermined well conditions.

Another object of the invention is to provide a well device, of the character described, which is automatically operated by the pressure differential thereacross and which is readily adjustable so as to be actuated by predetermined pressure differentials; said device being so constructed that, if desired, it may be run into and removed from the well by means of a flexible line or cable.

A particular object of the invention is to provide an improved well device for controlling the upward flow of well fluids through a production string, said device including a main flow passage having a valve element, which is actuated by the pressure differential thereacross, associated therewith and also having a minimum flow orifice above the valve element, whereby a flow may occur through the minimum flow orifice to control the actuation of the valve element.

A further object of the invention is to provide an improved control device, of the character de-

scribed, wherein the minimum flow orifice establishes communication between the well casing and the well tubing above the valve element, whereby when the liquid level in the casing falls to a predetermined point, gas is admitted to the tubing to lighten the liquid column therein and permit closing of said valve; the location or elevation of the minimum flow orifice being subject to variation, whereby the liquid level in the casing may be maintained at a predetermined point, in accordance with the location of said orifice.

Still another object of the invention is to provide an improved well device, of the character described, which may be connected with a suitable removable locking tool so that it may be removably supported at any desired elevation in the production string or which may be directly coupled in the production string and lowered therewith into the well bore.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a transverse, vertical, sectional view of a well device, constructed in accordance with the invention and illustrating the same mounted on the lower end of a running and locking assembly, which supports the device within the well tubing,

Figure 2 is an enlarged, transverse, vertical, sectional view of the device, showing the valve element in its closed position,

Figures 3 to 5 are horizontal, cross sectional views, taken on the lines 3—3, 4—4 and 5—5 respectively, of Figure 2,

Figure 6 is a view similar to Figure 1 showing a modified form of the invention with the valve element in its open position,

Figure 7 is an enlarged, transverse, vertical, sectional view of this form, with the valve element in its closed position, and

Figure 8 is a horizontal, cross-sectional view, taken on the line 8—8 of Figure 7.

In the drawings, the numeral 10 designates a tubular body or cage which is formed with an axial bore 11 extending entirely therethrough. The lower portion of the bore is enlarged as shown at 12, and above this enlarged portion the bore is reduced in diameter to provide a reduced passage 13. The annular shoulder 14 which is formed between the reduced passage 13

and the enlarged lower portion 12 of the bore is inclined or bevelled to form an annular inclined valve seat. A guide block 15 has its upper portion threaded into the lower enlarged end 12 of the bore of the body or cage 10 and this block is provided with an external shoulder 16. When the guide block is screwed upwardly into the body or cage, a suitable packing gasket or ring 17 is interposed between the shoulder 16 and the lower end of the body so as to seal the connection between the parts.

The guide block 15 is formed with an axial bore or opening 18 and a plurality of flow passages 19 surround the bore and extend vertically through the block 15, whereby a flow of fluid from below the block may pass upwardly through these passages and into the enlarged lower portion 12 of the bore of the body or cage 10. From the enlarged lower portion of the bore, the fluid may pass the valve seat 14 and then flow upwardly through the reduced passage 13 in the body.

For controlling the flow of fluid through the reduced passage 13, a valve element 20 is provided. This valve element includes an enlarged valve head 21 which has its upper portion rounded and adapted to engage the inclined or bevelled seat 14 within the body or cage 10. An elongate valve stem 22 which is preferably made integral with the valve head 21 and which depends therefrom, extends downwardly through the axial bore 18 of the guide block 15 and this stem is slidable within said bore. The lower end of the stem extends a considerable distance below the block 15 and is provided with screw threads 23. For constantly urging the valve element downwardly so as to move the valve head 21 away from its seat 14, a coiled spring 24 surrounds said stem below the guide block. This spring has its upper end engaging the bottom of the guide block 15, while its lower end rests upon a flanged washer 25 which is slidable on the stem 22. The flanged washer 25 is adjustably retained in position on the stem 22 by means of lock nuts 26 which are threaded onto the lower end of said stem. Manifestly, the coiled spring exerts its pressure to constantly urge the valve element 20 toward a lower position, as shown in Figure 1 and the spring pressure may be readily varied by adjusting the flanged washer 25 through the medium of the lock nut 26. The projecting lower end of the stem 22, together with the coiled spring 24 and its associate parts are enclosed by an elongate tubular sleeve or housing 27, which housing is provided with ports 28 in its side wall and with an axial port 29 in its bottom. The ports 28 and 29 are provided for the purpose of permitting an unrestricted flow from the exterior of said housing into the interior thereof. The upper end of the housing 27 may be suitably fastened to the guide block 15 but as illustrated, is threaded to the lower end thereof.

The assembly, as above described, is adapted to be lowered within the well tubing A, which tubing extends through the well casing B in the usual manner. The assembly may be lowered by any suitable means and in any suitable manner, but as shown in Figures 1 and 2, said device is connected to the lower end of a running and locking tool T. This tool is fully disclosed and described in my Letters Patent No. 2,246,811, issued June 24, 1941, and provides a means whereby the valve assembly may be run into the tubing on a wire line and suitably supported with-

in said tubing. Briefly, the running tool includes a tubular mandrel 30 which is provided with sealing cups 31 at its upper end and similar sealing cups 32 at its lower end. The upper end of the valve body or cage 10 is adapted to be threaded onto the lower end of this mandrel.

The upper end of the mandrel is connected to the tubular mandrel 33 of a locking assembly. This assembly includes radially expansible locking dogs 34 which are suspended from a carrier or sleeve 35 slidable on the mandrel 33. Upward displacement of the carrier and locking dogs from the mandrel 33 is prevented by an external annular shoulder 36 which is formed on the mandrel 33 and which is engaged by the dogs 34 when said dogs are moved upwardly relative to the mandrel.

The tool T also includes an elongate nipple or housing 37 which is connected in the tubing string A. This housing includes an annular recess 38 at its upper portion and said recess is provided with a shoulder 39 at its upper end. When the locking assembly is moved downwardly into the nipple, the locking dogs 34 are retracted so as to move into horizontal alinement with the recess 38. After the locking assembly has entered the housing, the locking dogs 34 may move downwardly on the mandrel 33, whereby said dogs are expanded radially outwardly, and upon an upward movement of the assembly said dogs engage the shoulder 39 so as to prevent upward displacement of the entire assembly, as is clearly shown in Figure 1.

The housing 37 is formed with radially extending inlet openings 40 which are disposed opposite the central portion of the mandrel 30, when the locking dogs are in their locking position, and these openings establish communication between the interior of the casing B and the annular space between the housing 37 and the mandrel 30 and between the sealing cups 31 and 32, whereby fluid may flow from the casing into this space surrounding the mandrel 30. The mandrel is formed with an inclined orifice 41, which will be hereinafter referred to as a minimum flow orifice and which serves to permit a reduced flow of fluid into the bore of the mandrel 30. By observing Figure 1, it will be obvious that the bore of the mandrel 30 communicates with the bore 11 of the valve body or cage 10 and also communicates with the bore of the mandrel 33 of the locking assembly. The upper end of the bore of the locking assembly mandrel is in direct communication with the bore of the tubing A. Therefore, an upward flow of fluid from the bore of the valve cage or body 10 may pass into the tubing string A.

In the operation of the device, the valve assembly is run into the well tubing A by means of the tool T and during the lowering of the apparatus, the surface connections or controls on the tubing are closed, whereby the well fluids are not flowing upwardly through said tubing. Of course, since the well is shut in, the liquid will be standing at a predetermined level, as controlled by well conditions, within the well casing A, which level is indicated by the dotted lines L in Figure 1. The housing 37, with which the running tool T coacts, is located below this standing liquid level of the well, whereby the valve assembly is disposed below such level when the tool T is locked within the housing, as has been explained. As the device is being lowered through the well and after it is supported therein, but prior to the time that the surface con-

nections on the tubing are opened, the valve element 20 will be in its open or lowered position, as shown in Figure 1, being held in such position by the coiled spring 24. The pressures across said valve are of course, equalized and said spring moves the valve element downwardly to its lowered or open position. When the surface connections on the tubing are opened, an upward flow of the well fluids will occur through the flow passages 19 in the guide block 15 and upwardly through the reduced passage 13 of the valve body or cage 10. From this point, the well fluids flow upwardly through the tubing string. There will also be a flow from the interior of the casing through the ports 40 in the housing 37 and through the minimum flow orifice 41 of the mandrel 30, such fluids admixing with the upwardly flowing fluid in said mandrel. It is contemplated that the combined flow area of the passages 19, together with the flow through the minimum flow orifice 41 permit an upward flow through the tubing string which is greater than the flow of well fluid from the producing formation into the lower end of the well casing. This results in the well liquid being removed through the tubing string at a rate in excess of the rate at which the well fluids are entering the lower end of the casing and therefore, the standing liquid level in the well casing will be lowered. Such lowering of the liquid level in the casing B will be aided by the gas head or the trapped gas in the casing above such level.

The flow passages 19 in the valve guide 15 act somewhat as a choke because they restrict the flow to a certain extent and therefore, when there is a flow through these passages, a pressure drop exists across them. However, it is noted that the restriction set up by the passages 19 is not sufficient to defeat aeration of the liquid by the gas; that is, a sufficient volume of fluid may pass through the passages 19 to assure that the velocity of the gas liberated from solution with the oil, together with the free gas, is at a rate sufficient to raise the liquids upwardly through the tubing. While the well fluids are flowing upwardly through the flow passages and then through the tubing string, the pressure drop across the passages 19 is not sufficient to cause the valve element 20 to move upwardly against the pressure of the spring 24 and therefore, during upward flow through said tubing, the valve 20 remains in a lowered or open position. The insufficiency of the pressure drop across the passages 19 is due to the low gas/oil ratio conditions of the column of fluid above the valve assembly. Since the column above the valve assembly is predominately liquid, the column is relatively heavy and the weight thereof, plus the pressure of the spring 24, is sufficient to hold the valve open against the pressure acting below the valve.

When flow has continued through the device for a sufficient length of time to lower the standing liquid level within the casing A to a point below the openings 40 in the housing 37, the gas which is trapped above the liquid level in the casing will enter the openings 40 and will then flow through the minimum flow orifice 41 and into the upwardly moving column of well fluid. The entrance of this gas into the liquid column will result in an aeration of the column, whereby the weight of said column is reduced. As soon as this occurs, the pressure above the valve element will be reduced accordingly, with

the result that the pressure differential across the flow passages 19 will be increased. When the valve is lowered, the lower portion of the head 21 of said valve is seated against the upper end of the bore 18 of the guide 15 and therefore the pressure drop across the flow passages 19 is applied to the area of the valve stem 22. When the pressure differential across the passages is built up to a sufficient point due to the reduction in the weight of the liquid column, then the valve element is moved upwardly, against the pressure of the spring 24 and such upward movement causes the valve head 21 to engage the seat 14 and thereby shut off a further flow upwardly through the valve body 10 and also through the flow passages 19.

After the valve is seated to close the flow through the bore 13, the only flow which can occur is through the minimum flow orifice 41 and, as has been explained, the area of this orifice is such that the flow passing therethrough is less than the flow of well fluid which is entering the bottom of the casing B from the producing formation, whereby, the liquid level in the casing B will be again built up. Of course, gas will enter through the orifice 41 until the level of the liquid rises thereabove, after which liquid will flow through said orifice. The orifice is of such small size that the volume of liquid passing therethrough is insufficient to liberate enough gas to produce the necessary velocity for lifting said liquid through the tubing and therefore, a liquid column is built up within the tubing above the valve element. The valve element 20 will remain in its closed position until the column is built up within the tubing string to a point where the hydrostatic head or weight of said column is sufficient, along with the pressure of the spring 24, to again cause the valve to move downwardly to an open position. It is pointed out that if the diameter of the valve seat 14 is greater than that of the valve stem, the pressure which must be built up above the valve assembly must be greater than the pressure at which the valve closed because, as has been explained, when the valve is open, the effective area acted upon by the pressures is the area of the stem.

From the above, it will be seen that the valve is normally held open by the spring 24 to permit an upward flow through the tubing string A. This flow is continued until the liquid level within the well casing falls to a predetermined point and when such point is reached, the valve element is automatically moved to a closed position to shut off the flow, such closure being effected by aeration of the column above the valve. The valve remains in a closed position until the liquid level has again built up within the well casing, after which the valve opens to repeat the cycle. The valve is actuated by the pressure differential thereacross and the provision of the spring 24 which may be readily adjusted, makes the device practical under various well conditions. It is obvious that the gas head which is normally present in the upper end of the well casing is utilized to effect operation of the valve to permit closing thereof. The liquid level in the casing can never fall below the minimum flow orifice 41 and therefore, a liquid seal is constantly maintained around the tubing inlet, with the result that the escape or production of gas alone, without oil, from the producing formation is retarded and substantially prevented. Thus, the gas in the formation is conserved to prolong the life of the flowing well. The posi-

tion of the minimum flow orifice 41 is subject to variation and the elevation of this flow orifice will effect the closure of the valve element at the desired, predetermined level of the liquid in the casing.

As above pointed out, the valve assembly may be lowered into the well tubing by any suitable means and the invention is not to be limited to any particular type of running tool. In Figures 6 to 8 a slightly modified form of the invention, together with another type of running device is illustrated. In this form, the running tool R includes an elongate tubular mandrel 50 which is provided with pressure seal packing elements 51 on its lower portion. Above the packing cups, the mandrel has a slip expanding portion 52 which is arranged to coact with gripping slips 53 which are slidably mounted on the mandrel. The slips are carried by a suitable carrier or sleeve 54 and upward displacement of the carrier and slips is prevented by an external flange 55 which is formed on the mandrel. This tool is clearly shown and described in my prior Patents Nos. Re. 20,546 and 1,972,791 and obviously, may be locked within the tubing at any elevation therein. When this type of tool is used, it is not necessary to provide the coacting nipple or housing 37 of the first form.

The valve assembly of this form of the invention is substantially the same as the first form shown in Figures 1 to 5 with the exception that a valve body 100 is substituted for the valve body or cage 10. The body 100 has its upper end extended and this upper end is threaded onto the lower end of the mandrel 50 of the tool R. Below the internal screw threads at the upper end of the bore of the body 100, additional screw threads 101 are formed, whereby a valve retaining collar 102 may be mounted within the upper ends of the bore of said body. A ball check valve 103 is confined below the retaining member 102 and is adapted to engage an internal seat 104 which is formed at the upper end of the restricted passage 113 of the valve body. For establishing a communication between the exterior of the valve assembly and the bore 113 when the valve element is in its closed position, a restricted or minimum flow passage 141 is provided in the body 100. This minimum flow passage takes the place of the minimum flow passage 41 described in the first form of the invention. The remainder of the valve assembly in the form shown in Figures 6 and 7 is identical to the valve assembly shown in Figures 1 and 2.

The operation of this form of the invention is substantially the same as the first form. Normally, the valve element 20 is unseated, as shown in Figure 6 and an upward flow through the flow passages 19 is permitted. Such upward flow will of course unseat the ball check valve 103 and will then enter the tubing string. When the liquid level in the well casing falls to a predetermined point, gas is permitted to enter the minimum flow orifice 141 with the result that the liquid column is aerated and its weight reduced, thereby permitting the valve element 20 to move to its closed position, as shown in Figure 7. When this occurs, flow through the passages 19 is shut off and well fluids are admitted through the minimum flow orifice 141. When the pressure above the valve element 20 is again built up, said element moves downwardly to an open position and the cycle is repeated.

The provision of the ball check valve 103, which valve is located above the minimum flow

orifice 141, is not essential to the invention. However, when the well is shut in at the surface, the liquid which has been accumulated in the tubing string above the check valve 103 cannot drain downwardly through the tubing and back into the well or into the producing formation. In other words, the purpose of the valve 103 is to prevent a back flow of liquid through the tubing string when the surface connections are closed to shut in the well. However, the use of the check valve is optional and may be omitted if desired.

In both forms of the invention, the intermitting device is illustrated as connected to a suitable running tool, whereby it may be readily run into or removed from the well by means of a flexible line. However, the invention is not to be limited to positioning the assembly by means of such a tool for obviously, the valve body 10 in the first form and 100 in the second form could be directly coupled to the well tubing string, in which case the assembly would be lowered with the tubing and would not be independently removable from the well.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A flowing well control device wherein a tubing mounted in a well casing has a fluid inlet at its lower end, including in combination, a valve normally biased to open position mounted in the tubing string and responsive to the pressure differential thereacross for controlling the flow of well fluids upwardly through the tubing, means for establishing a predetermined pressure differential across the valve to maintain the valve in its open position permitting an upward flow through the tubing string, and a fluid inlet to the tubing above the valve restricted to admit a reduced flow of fluid from the casing into the tubing, said fluid inlet constantly admitting fluid, regardless of the position of the valve, the admitted flow acting on the valve to vary the predetermined differential to effect actuation of said valve to closed position.

2. A well control device for flowing wells including, a well casing, a well tubing having a well fluid inlet mounted within the casing, a valve mounted in the tubing above the inlet and responsive to the differential in pressures thereacross for controlling the flow through the tubing, resilient means urging the valve to an open position, whereby a predetermined pressure differential across the valve is required to actuate the same, and a fluid inlet to the tubing above said valve restricted to meter the flow of fluid from the casing to the tubing, said fluid inlet constantly admitting fluid to the tubing, the admittance of gaseous fluid through the restricted fluid inlet acting to lighten the column of flowing fluid above the valve to increase the pressure differential thereacross and permit closing of the valve to shut off flow through the tubing.

3. A well control device for flowing wells including, a well casing, a well tubing having a well fluid inlet mounted within the casing, a valve mounted in the tubing above the inlet and responsive to the differential in pressures there-

across for controlling the flow through the tubing, resilient means urging the valve to an open position, whereby a predetermined pressure differential across the valve is required to actuate the same, a fluid inlet to the tubing above said valve restricted to meter the flow of fluid from the casing to the tubing, the admittance of gaseous fluid through the restricted fluid inlet acting to lighten the column of flowing fluid above the valve to increase the pressure differential thereacross and permit closing of the valve to shut off flow through the tubing, and separate means exposed to the well fluids for causing the valve to reopen.

4. A well control device for flowing wells including, a well casing, a well tubing having a well fluid inlet mounted within the casing, a valve mounted in the tubing above the inlet and responsive to the differential in pressures thereacross for controlling the flow through the tubing, resilient means urging the valve to an open position, whereby a predetermined pressure differential across the valve is required to actuate the same, and a fluid inlet to the tubing above said valve restricted to meter the flow of fluid from the casing to be tubing, the admittance of gaseous fluid through the restricted fluid inlet acting to lighten the column of flowing fluid above the valve to increase the pressure differential thereacross and permit closing of the valve to shut off flow through the tubing, said restricted fluid inlet acting to admit liquid to the tubing above the valve after the valve has closed, whereby a liquid column is built up to again open the valve when said column exerts a predetermined hydrostatic head on the valve.

5. A flowing well control device wherein a tubing mounted in a well casing has a fluid inlet at its lower end, including in combination, a valve normally biased to open position mounted in the tubing string and responsive to the pressure differential thereacross for controlling the flow of well fluids upwardly through the tubing, means for establishing a predetermined pressure differential across the valve to maintain the valve in its open position permitting an upward flow through the tubing string, and constantly open means for admitting gas from the casing into the tubing above the valve to lighten the column of flowing fluid and thereby change the differential across the valve to close said valve, said gas being admitted to the tubing when the liquid level in the casing falls below a predetermined point, whereby a liquid seal is constantly maintained around the well fluid inlet to the tubing and to effect actuation of the valve to closed position.

6. A well control device including, a well fluid conductor having a well fluid inlet for conducting well fluids from the lower end of a well bore to the surface, a valve seat within said conductor, a valve element normally biased toward open position and movable relative to said seat for controlling the flow through the conductor, said element having its upper end exposed to the pressure in the conductor above the element and its lower end exposed to the pressure in the conductor therebelow, whereby the element is actuated by the differential in such pressures, and a fluid inlet for constantly admitting well fluids into the conductor above the valve whereby such well fluids are added to the column above the valve to vary the differential across the valve and thereby effect actuation of said valve to closed position.

7. A well control device including, a well fluid conductor having a well fluid inlet at its lower

end communicating with the producing formation for conducting well fluids to the surface, a valve body mounted in the conductor and having its bore communicating with the bore of the conductor, a guide block mounted within the body and having flow passages therein for permitting an upward flow through the body, said passages setting up a predetermined pressure drop thereacross, a valve element slidable in the block with its upper end exposed to the pressure in the conductor thereabove and its lower end exposed to the pressure in the conductor below the guide block, whereby the element is actuated by the differential in such pressures, and a fluid inlet to the conductor above the valve element restricted to admit well fluids to the tubing above said valve, said admitted fluid acting on the column of flowing fluid when the valve is open to effect closure thereof and acting on the valve when the same is closed to effect opening thereof.

8. A well control device including, a well casing having its lower end communicating with the producing formation and its upper end closed, a well tubing extending through the well casing and having its lower end communicating with the casing, whereby well fluids may flow upwardly through the tubing to the surface, a valve seat within the tubing string, a valve element normally biased toward open position mounted within the tubing and movable relative to said seat for controlling upward flow through the tubing, said valve being responsive to the pressure differential thereacross, and a constantly open restricted fluid inlet to the tubing above the valve and independent of the latter for establishing communication between the casing and tubing, said inlet functioning to admit gas from the casing into the tubing when the liquid level in the casing falls to a predetermined point, whereby the admitted gas lightens the flowing column of fluid in the tubing to vary the pressure differential across the valve element and effect closure thereof.

9. A well control device including, a well casing having its lower end communicating with the producing formation and its upper end closed, a well tubing extending through the well casing and having a well fluid inlet communicating with the casing, whereby well fluids may flow upwardly through the tubing to the surface, a valve seat within the tubing string above the well fluid inlet, a valve element normally biased toward open position mounted within the tubing and movable relative to said seat for controlling upward flow through the tubing, said valve being responsive to the pressure differential thereacross, means for establishing a predetermined pressure differential across the valve, whereby the valve is normally open to permit flow, and a reduced fluid inlet to the tubing above the valve and independent of the latter for establishing constant communication between the casing and tubing regardless of the position of the valve, said inlet functioning to admit gas from the casing into the tubing when the liquid level in the casing falls to a predetermined point, whereby the admitted gas lightens the flowing column of fluid in the tubing to effect closure of the valve element, the inlet also acting to admit liquid to the tubing after the valve is closed, whereby a liquid column sufficient to effect re-opening of said valve is built up.

10. A well control device including, a well casing having its lower end communicating with the producing formation and its upper end closed, a well tubing extending through the well casing and having a well fluid inlet communicating with

the casing, whereby well fluids may flow upwardly through the tubing to the surface, a valve seat within the tubing string above the well fluid inlet, a valve element mounted within the tubing and movable relative to said seat for controlling upward flow through the tubing, said valve being responsive to the pressure differential thereacross, resilient means associated with the valve urging said valve toward its open position, and a restricted fluid inlet to the tubing above the valve for establishing constant communication between the casing and regardless of the position of the valve tubing, said inlet functioning to admit gas from the casing into the tubing when the liquid level in the casing falls to a predetermined point, whereby the admitted gas lightens the flowing column of fluid in the tubing to effect closure of the valve element against the pressure of the resilient means, the restricted fluid inlet also acting to permit equalization of pressures across the valve after the same is closed to permit the resilient means to re-open said valve.

11. A well control device including, a well casing having its lower end communicating with the producing formation and its upper end closed, a well tubing extending through the well casing and having a well fluid inlet communicating with the casing, whereby well fluids may flow upwardly through the tubing to the surface, a valve seat within the tubing string above the well fluid inlet, a valve element mounted within the tubing and movable relative to said seat for controlling upward flow through the tubing, said valve being responsive to the pressure differential thereacross, resilient means associated with the valve urging said valve toward its open position, a restricted fluid inlet to the tubing above the valve for establishing constant communication between the casing and tubing, said inlet functioning to admit gas from the casing into the tubing when the liquid level in the casing falls to a predetermined point, whereby the admitted gas lightens the flowing column of fluid in the tubing to effect closure of the valve element against the pressure of the resilient means, the restricted fluid inlet also acting to permit equalization of pressures across the valve after the same is closed to permit the resilient means to re-open said valve, and means for adjusting the resilient means to control the pressure differential at which the valve operates.

12. A well device, of the character described, including a well casing, a well tubing having a well liquid inlet communicating with the casing to permit the well fluids from the casing to enter said tubing and flow upwardly therein, and a valve assembly mounted in the tubing above the inlet and having a valve element normally biased toward open position disposed in the line of flow through the tubing so as to be actuated by the differential in pressures above and below the element, said element being arranged to close upon the exertion of a predetermined pressure differential thereacross, the tubing having a restricted port above the valve element independent of the latter for establishing constant communication between the tubing and casing and for admitting gas to the tubing when the liquid level in the casing falls to a point immediately below the restricted port, admission of gas to the tubing setting up the necessary pressure differential across the valve element to effect closing of the valve and thereby prevent the liquid level in the casing falling below the well liquid inlet of the tubing

to maintain a liquid seal around the liquid inlet to the tubing.

13. A well device of the character described, including a well casing, a well tubing having a liquid inlet communicating with the casing to permit the well fluids from the casing to enter said tubing and flow upwardly therein, a valve assembly mounted in the tubing above the inlet and having a valve element normally biased toward open position disposed in the line of flow through the tubing so as to be actuated by the differential in pressures above and below the element, said element being arranged to close upon the exertion of a predetermined pressure differential thereacross, the valve assembly having a restricted port above the valve element and independent of the latter for establishing constant communication between the tubing and casing and for admitting gas to the tubing when the liquid level in the casing falls to a predetermined point, the admission of gas to the tubing setting up the necessary pressure differential across the valve element to effect closing of the valve and thereby maintain a liquid seal around the liquid inlet to the tubing, the restricted port also functioning to admit fluid to the tubing after the valve is closed to build up a fluid column therein and thereby reduce the differential across the valve element and thereby permit re-opening thereof.

14. A well device of the character described, including a well casing, a well tubing having a liquid inlet communicating with the casing to permit the well fluids from the casing to enter said tubing and flow upwardly therein, a valve assembly mounted in the tubing above the inlet and having a valve element normally biased toward open position disposed in the line of flow through the tubing so as to be actuated by the differential in pressures above and below the element, adjustable means associated with the valve element for permitting closure thereof at a predetermined pressure differential thereacross, the valve assembly having a restricted port above the valve element and independent of the latter for establishing constant communication between the tubing and casing and for admitting gas to the tubing when the liquid level in the casing falls to a predetermined point, the admission of gas to the tubing setting up the necessary pressure differential across the valve element so as to effect closing of the valve and thereby maintain a liquid seal around the liquid inlet to the tubing.

15. A well device, of the character described, including a well casing, a well tubing having a well liquid inlet communicating with the casing to permit the well fluids from the casing to enter said tubing and flow upwardly therein, a valve assembly mounted in the tubing above the inlet and having a valve element disposed in the line of flow through the tubing so as to be actuated by the differential in pressures above and below the element, said element being arranged to close upon the exertion of a predetermined pressure differential thereacross, the tubing having a restricted port above the valve element for establishing constant communication between the tubing and casing and for admitting gas to the tubing when the liquid level in the casing falls to a point immediately below the restricted port, the admission of gas to the tubing setting up the necessary pressure differential across the valve element to close the valve and thereby prevent the liquid level in the casing falling below the well liquid inlet of the tubing to maintain a liquid seal around the liquid inlet to the tubing, and check-

valve means in the tubing above the restricted port for preventing a back flow of fluids downwardly through the tubing.

16. A well device, of the character described, including a well casing, a well tubing having a well liquid inlet communicating with the casing to permit the well fluids from the casing to enter said tubing and flow upwardly therein, and a valve assembly mounted in the tubing above the inlet and having a valve element disposed in the line of flow through the tubing so as to be actuated by the differential in pressures above and below the element, said element being arranged to close upon the exertion of a predetermined pressure differential thereacross, means attached to the valve assembly for removably locking the same within the tubing, the tubing having a restricted port above the valve element for establishing communication between the tubing and casing and for admitting gas to the tubing when the liquid level in the casing falls to a point immediately below the restricted port, the admission of gas to the tubing setting up the necessary pressure differential across the valve element to close the valve and thereby prevent the liquid level in the casing falling below the well liquid inlet of the tubing to maintain a liquid seal around the liquid inlet to the tubing.

17. A well flowing control device including, a fluid conductor having means for mounting it in the flow pipe of a well and provided with a fluid

inlet port located intermediate its ends and constantly open, a seal above the inlet for closing off the space between the conductor and the pipe, and a valve mounted in the conductor below the inlet port thereof and having means for holding it open during lowering of the device and during normal flow, said valve opening means having an adjustment to set said means to yield when the pressure differential across said valve is unequalized to a degree whereby the upwardly flowing well fluid will close said valve.

18. A well flowing device including, a fluid conductor, means for connecting the conductor with a well tubing and establishing flowing communication therewith, said conductor having a constantly open fluid inlet intermediate its ends, a valve seat in the conductor below the inlet, the conductor having a well fluid inlet below the valve seat, a valve in the conductor between the valve seat and the inlet therebelow adapted to engage said seat, and means connected with the valve for controlling actuation thereof including a restraining element for maintaining said valve open during a predetermined rate of flow of well fluid upwardly through said valve seat and a restricted fluid passage correlated with the valve to maintain a predetermined pressure differential across said passage, whereby the upwardly flowing fluid seats the valve upon an increased pressure differential.
